COMBINED CLOCK, LAMP, AND PLANTER

George D. Powell, Del Paso Heights, Calif.

Application October 21, 1955, Serial No. 38,515

Term of patent 14 years

(Cl. D35—3)

Figure 1 is a front elevational view of a combined clock, lamp, and planter showing my new design; Figure 2 is an end elevational view; and Figure 3 is a top plan view thereof.
I claim:
The ornamental design for a combined clock, lamp, and planter, as shown.
